(57) **CLAIM**

We claim the ornamental design for a flow cell cartridge, as shown and described.

DESCRIPTION

FIG. 1 is a top, rear perspective view of a flow cell cartridge comprising our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is an enlarged rear elevational view thereof.

The evenly broken lines shown in the drawings illustrate portions of the flow cell cartridge that form no part of the claimed design.
